(57) **ABSTRACT**

The present invention discloses a terminal module and a high-speed electrical connector using the same. The connector includes a number of terminal modules, a number of shielding plates, a front cover and a rear stiffener. The terminal module has grounding terminals and differential signal pairs embedded within an insulating body. Each differential signal pair have contacting portions, mounting portions and connecting portions. The insulating body defines a number of cutouts thereon with the connecting portions of the differential signal pairs partially exposed therefrom. The front cover has a U-shaped cross-section. An exposed surface of the connecting portion of the differential signal pairs is coated with an insulating thin film.

TERMINAL MODULE AND HIGH-SPEED ELECTRICAL CONNECTOR USING THE SAME

CROSS REFERENCE TO RELATED APPLICATIONS

The present application claims the priority of Chinese patent application serial No. 202220216023.6, filed Jan. 26, 2022 in the SIPO (State Intellectual Property Office of the P.R.C.); and Chinese patent application serial No. 202220216078.7, filed Jan. 26, 2022; and Chinese patent application serial No. 202220216008.1, filed Jan. 26, 2022; and Chinese patent application serial No. 202210093088.0, filed Jan. 26, 2022; and Chinese patent application serial No. 202210094128.3, filed Jan. 26, 2022; and Chinese patent application serial No. 202210094112.2, filed Jan. 26, 2022. The present application also relates to a U.S. patent application filed in the same day as the instant application and entitled as "Shielding Means and High-Speed Electrical Connector Using the Same" with the same inventorship and applicant(s). The content of above-referenced patent applications is incorporated by reference herein in its entirety.

BACKGROUND

1. Technical Field

The present disclosure relates to an electrical connector, and more particularly, to a terminal module and a high-speed electrical connector using the same.

2. Description of Related Art

Backplane connectors are widely used in communication technology, which is a common type of connector for large communication equipment, ultra-high-performance servers and giant computers, industrial computers, and high-end storage devices, etc. Backplane connectors typically include a number of signal modules arranged along the left-to-right directions. Each signal module usually has an insulator, a plurality of differential signal terminal pairs. The signal pairs are arranged along the top-to-bottom directions and are fixed to the insulator. The conventional backplane connector employs two shields assembled on two opposite sides of the insulator along the left-to-right directions. However, conventional backplane connectors have drawbacks in crosstalk resistance as well as insertion loss reduction.

Hence, it is desirable to provide an improved shielded high-speed electrical connector.

SUMMARY

The present disclosure provides a terminal module for assembly into a high-speed, electrical connector adapted to connecting a complementary connector. The high-speed electrical connector has a shielding plate stacked assembled with the terminal module. The terminal module comprises a terminal assembly including an insulating body and a plurality of conductive terminals which having contacting portions, mounting portions and connecting portions interconnecting the contacting portions and mounting portions. The insulating body defines a plurality of cutouts thereon with the connecting portions partially exposed therein. An exposed surface of the connecting portion is coated with an insulating thin film.

The present disclosure also provides a high-speed electrical connector adapted for engaging with a complementary connector. The connector includes a plurality of terminal modules, a plurality of shielding plates, a front cover and a rear stiffener. Each terminal module comprises grounding terminals and differential signal pairs embedded within an insulating body. Each differential signal pair have contacting portions, mounting portions and connecting portions for connecting the contacting portions with the mounting portions. The insulating body defines a plurality of cutouts thereon with the connecting portions of the differential signal pairs partially exposed therefrom. Each shielding plate is stacked arranged between every two adjacent terminal modules. The front cover is configured for organizing the plurality of terminal modules and the plurality of shielding plates. The front cover has a U-shaped cross-section. The grounding terminals and the differential signal pairs are partially accommodated within the front cover. The rear stiffener is configured for fixing the terminal modules and the shielding plates together from a rear side thereof. An exposed surface of the connecting portion is coated with an insulating thin film.

The foregoing has outlined rather broadly the features and technical advantages of the present disclosure in order that the detailed description of the invention that follows may be better understood. Additional features and advantages of the invention will be described hereinafter which form the subject of the claims of the invention.

BRIEF DESCRIPTION OF THE DRAWINGS

The components in the drawing are not necessarily drawn to scale, the emphasis instead being placed upon clearly illustrating the principles of the described embodiments. In the drawings, reference numerals designate corresponding parts throughout various views, and all the views are schematic.

FIG. 1 is a perspective view of an electrical connector in accordance with a first embodiment of the present disclosure;

FIG. 2 is a perspective view of the electrical connector as shown in FIG. 1 while taken from a different aspect;

FIG. 3 is a perspective view of a shell of the electrical connector as shown in FIG. 1;

FIG. 4 is a perspective view of a contact wafer of the electrical connector as shown in FIG. 1;

FIG. 5 is a perspective view of the contact wafer as shown in FIG. 4 while taken from a different aspect;

FIG. 6 is a perspective view of a contact assembly of the electrical connector as shown in FIG. 1;

FIG. 7 is an enlarged perspective view of the contact assembly of FIG. 6;

FIG. 8 is a schematic view of the contact wafers and the shielding elements of the electrical connector as shown in FIG. 1 after assembling;

FIG. 9 is a perspective view of an insulative housing of the electrical connector as shown in FIG. 1;

FIG. 10 is a perspective view of the insulative housing as shown in FIG. 9 while taken from a different aspect;

FIG. 11 is a perspective view of the shielding element of the electrical connector as shown in FIG. 1;

FIG. 12 is an assembled perspective view of one contact wafer and one shielding element of the electrical connector as shown in FIG. 1;

FIG. 13 is a perspective view of rear cover of the electrical connector as shown in FIG. 1;

FIG. 14 is a perspective view of the rear cover as shown in FIG. 13 taken along a different aspect;

FIG. 15 is a view of the contact wafer of the electrical connector in accordance with a second embodiment;

FIG. 16 is a perspective view of an electrical connector assembly of the present disclosure.

DETAILED DESCRIPTION OF ILLUSTRATED EMBODIMENTS

Reference will now be made to the drawing figures to describe the embodiments of the present disclosure in detail. In the following description, the same drawing reference numerals are used for the same elements in different drawings.

Referring to FIG. 1 and FIG. 2, an electrical connector 100 in accordance with the present invention, comprises a front shell 10, a plurality of terminal modules 20 assembled on the front shell 10, a plurality of shielding elements 30, a back shell 40 for fixing the terminal modules 20 and an insulating base 50. Particularly, three directions shown in the FIG. 1 are AA in the first direction, BB in the second direction, and CC in the third direction. The relationship between the three directions is perpendicular to each other.

Referring to FIG. 3 together with FIG. 1, FIG. 2, the front shell, which is also can be named as front cover 10, comprises a mating wall 11 and side walls 12. The mating wall 11 and the side walls 12 are jointly enclosed to define a containing space 13 to contain the terminal module 20 and the shielding elements 30. The mating wall 11 is configured to cooperate with the complementary connector (not shown), which has a plurality of mating holes 111 arranged in matrix. The plurality of mating holes 111 extend along a first direction AA through the mating wall 11, and communicate to the containing space 13. The first direction AA is the direction along which the electrical connector 100 engages to the complementary connector. The side wall 12 is provided with guiding portions 121, which are used to guide the complementary connector to insert into the electrical connector 100, and first fixing portions 122. In the preferred embodiment, each side wall 12 is provided with a plurality of guide portions 121. Preferably, the spacing between the two neighbored guide portions 121 on one side wall 12 is greater than the spacing between the two neighbored guide portions 121 on the other side wall 12. By such an arrangement, it can not only guide the complementary connector engaging with the electrical connector 100, but also can avoid a mis-inserting therebetween. In the present embodiment, the guiding portions 121 are designed to be a plurality of guiding slots along a first direction AA. Understandably, in other embodiments, the guiding portions 121 can be designed to be a plurality of guiding protrusions protruded from the side wall 12 and arranged along a first direction AA. The first fixing portion 122 is located at one end of the side wall 12 away from the mating wall 11, which is adapted for cooperating with the terminal module 20 and fixing the terminal module 20 on the front shell 10. In the present embodiment, the number of side walls 12 is two, but it will be appreciated that in other embodiments, the number of sidewalls 12 may be set as needed. More detailedly, the side walls 12 of the preferred embodiment has a top sidewall and a bottom sidewall. In this preferred embodiment, the front shell/cover 10 has a U-shaped cross-section.

Referring to FIG. 4, FIG. 5 and FIG. 1, the plurality of terminal modules 20 are arranged along the third direction CC which is perpendicular to the first direction AA. The terminal module 20 includes a terminal assembly 60 and an

insulating wafer/body 70 for fixing the terminal assembly 60. Referring to FIG. 6 and FIG. 7, the terminal assembly 60 includes a plurality of ground terminals/contacts 61 and a plurality of differential signal terminal pairs. The differential signal terminal pair is disposed between adjacent ground terminals 61. Since the differential signal terminal pair is disposed along the second direction BB and arranged between the adjacent two ground terminals 61 in the same terminal module 20, the signal interference between the adjacent two differential signal terminal pairs can be shielded, thereby enhancing the electromagnetic isolation between the differential signal terminal pairs, improving insertion loss and reducing signal crosstalk.

The grounding terminal 61 includes a first contacting portion 611, a first mounting portion 612 and a first connection portion 613 connecting the first contacting portion 611 and a first mounting portion 612. The first contacting portion 611 extends outwards from one side of the first connection portion 613 along the first direction AA, the first mounting portion 612 extends outwards from the other side of the first connection portion 613 in the fourth direction. In the present embodiment, the fourth direction coincides with the second direction BB. The first mounting portion 612 is used to engage with a printed circuit board on which the electrical connector is mounted thereon. However, it will be appreciated that in other embodiments, the fourth direction may also coincide with the second direction BB, e.g., an acute angle is formed between the fourth direction and the second direction BB. Referring to FIG. 7, the first contacting portion 611 includes a first contacting arm 6111 electrically connecting with a first grounding means and a second contacting arm 6112 electrically connecting with a second grounding means. In the present embodiment, the first grounding means is grounding terminals of the complementary connector, and the second grounding means is the shielding element 30. When the electrical connector 100 is engaged with the complementary connector, the first grounding means and the second grounding means are located on both sides of the first connection portion 613 in the thickness direction of the first connection portion 613. Since the ground terminal 61 is electrically connected to the shielding element 30, adjacent shielding elements 30 electrically connects with each other thereby establishing a grounding circle. The first contacting arm 6111 is formed from the side of the first connection 613 along the first direction AA outward extension formed. The first contact arm 6111 includes a contacting finger 6114 and a pair of connecting arms 6115 extending backwards from the contacting finger 6114. A slot 6113 is defined between the pair of connecting arms 6115. In the preferred embodiment, the second contacting arm 6112 is formed by stamping from the grounding terminal 61, therefore the stamped slot is formed the slot 6113. The first contacting arm 6111 and the second contacting arm 6112 are in a straight line in the first direction AA, thereby effectively shortening the length of the terminal assembly 60 in the second direction BB.

Referring to FIG. 8, a contact region between the first contacting arm 6111 and the grounding terminal of the complementary connector is defined as the first contact region, and similarly, the contact region between the second contacting arm 6112 and the shielding element 30 is defined as the second contact region. Along the thickness direction of the first connecting portion 613 (i.e., the third direction CC), the first contact region, the second contact region are located on opposite sides of the first connecting portion 613. In the present embodiment, at least one of the first contacting arm 6111, the second contacting arm 6112 is an elastic

contacting arm. However, it will be appreciated that, in other embodiments, at least one of the first contacting arm **6111** and the second contacting arm **6112** may also be provided as a rigid contacting arm.

Referring to FIG. 6, the first connection portion **613** is curved so that the extending direction of the first contacting portion **611** is not parallel to the extending direction of the first mounting portion **612**. In the present embodiment, the extending direction of the first contacting portion **611** is perpendicular to the extending direction of the first mounting portion **612**. However, it will be appreciated that, in other embodiments, the extending direction of the first contacting portion **611** and the extending direction of the first mounting portion **612** may also not be perpendicular, e.g., the two portions are parallel or the angle between the two portions is an acute angle. The first mounting portion **612** is soldered to the circuit board, which may be a fisheye solder pin, a needle solder pin, an SMT solder pin, or a convex bag.

Referring to FIG. 6 and FIG. 7, the differential signal terminal pair comprises two differential signal terminals **62**. The differential signal terminal **62** includes a second contacting portion **621**, a second mounting portion **622** and a second connection portion **623** connecting the second contacting portion **621** and a second mounting portion **622**. The first contacting arm **6111**, the second contacting portion **621** is arranged along the second direction BB. The contacting area between the second contacting portion **621** and the signal terminal of the complementary connector is deemed as a third contact region. Referring to FIG. 8, in the thickness direction of the first connection portion **613** (i.e., the third direction CC), the first contact region, the third contact region are located at the same side of the first connection portion **613**, the second contact region is located on the other side of the first connection portion **613**. The second connection portion **623** is curved so that the extending direction of the second contacting portion **621** is not parallel to the extending direction of the second mounting portion **622**. In the present embodiment, the extending direction of the second contacting portion **621** is perpendicular to the extending direction of the second mounting portion **622**. However, it will be appreciated that, in other embodiments, the extending direction of the second contacting portion **621** and the extending direction of the second mounting portion **622** may also not be perpendicular to each other, e.g., the two portions are parallel or the angle between the two portions is an acute angle. The second mounting portion **622** is soldered to the circuit board, which may be a fisheye solder pin, a needle solder pin, an SMT solder pin, or a convex bag.

Referring to FIG. 9 and FIG. 10, the insulating wafer **70** is used to hold the first connection portion **613**, the second connection portion **623**, to thereby fix the ground terminal **61** and the differential signal terminals **62** thereto. The insulating wafer **70** is provided with a cutout **71**. The cutout **71** extends through the insulating wafer **70** along the thickness direction thereof (i.e., the third direction CC). The cutout **71** is used to make the first connection portion **613** and the second connection portion **623** partially exposed to air. Since the dielectric constant of the air is less than the dielectric constant of the insulating material, therefore, by such a design, it may reduce the insertion loss of the electrical connector **100**, and increase the transmission speed of the signals. Preferably, the part of the terminal assembly **60** which is exposed from the cutout **71** is provided with an insulating film. The insulating film can effectively avoid the problem of poor insulation withstand voltage or

short circuit caused by free or stationary wire or metal chips produced during manufacturing the electrical connector. Preferably, the thickness of the insulating film is 0.01 mm to 0.1 mm. In the present embodiment, the first connection portion **613** and the second connection portion **623** are partially located within the cutout **71**. Referring to FIG. 5 as shown in FIG. 10, the insulating wafer **70** is provided with a first concession slot **72** near the second contacting portion **621**. In the first direction AA, the first concession slot **72** is directly facing to the second contacting portion **621**. When the electrical connector **100** is engaged to the complementary connector, the signal terminal of the complementary connector is located in the first concession slot **72**.

Referring to FIG. 5 together with FIG. 10, the insulating wafer **70** is provided with a second concession slot **73** near the first contact arm **6111**. In the first direction AA, the second concession slot **73** is directly facing to the first contact arm **6111**. When the electrical connector **100** is engaged to the complementary connector, the ground terminal of the complementary connector is located in the second concession slot **73**. Referring to FIG. 4 and FIG. 9, similarly, the insulating wafer **70** is provided with a third concession slot **74** near the second contact arm **6112**. In the first direction AA, the third concession slot **74** is directly facing to the second contact arm **6112**, and the second contact arm **6112** is at least partially located within the third concession slot **74**.

Referring to FIG. 9 and FIG. 10, the insulating wafer **70** is provided with a second fixing portion **751** and a retaining recess **752** on one side opposite to the top side wall **12**. The second fixing portion **751** is mated to the first fixing portion **122** to mount the terminal module **20** fixed on the front shell/cover **10**. In the present embodiment, the first fixing portion **122** is a fixing groove, the second fixing portion **751** is a fixed protrusion in conjunction with the fixing groove. Preferably, the fixed protrusion is provided with a guide portion **7511** to guide the fixed protrusion into the fixing groove **122**. Referring to FIG. 9 and FIG. 10, the insulating wafer **70** extends outwards along the second direction BB to form an extension arm **753** and a stopper **754** located at the end of the extension arm **753** away from the insulating wafer **70**. The extension arm **753**, the stop **754** and the insulating wafer **70** together form the retaining recess **752**. The retaining recess **752** is provided with an opening **7521** on one side facing the adjacent terminal modules **20**. In the present embodiment, the extension arm **753**, the stopper **754** and the insulating body **70** together form two retaining recesses **752**. Along the third direction CC, the two retaining recesses **752** are located on opposite sides of the extension arm **753**.

Referring to FIG. 11, FIG. 12 together with FIG. 1, the plurality of shielding elements/means/plates **30** are arranged along the third direction CC. The terminal module **20** is disposed between the adjacent two shielding elements **30**. The shielding element **30** is provided with a fixing hole **301**, the insulating body **70** is provided with a fixed column **701** in conjunction with the fixing hole **301**. The fixing hole **301** is mated to the fixing post **701** to mount the shielding element **30** fixed on the insulating body **70**. The shielding element **30** includes a plate section **31**, a mating section **32** extending outwards from the plate section **31** the first direction AA, and a mounting section **33** formed by extending outward in the second direction BB from the plate section **31**. The plate section **31** has a protruding portion **311** protruded outwards therefrom along the third direction CC that perpendicular to the first direction AA and the second direction BB. Preferably, the protruding portion **311** is electrically connected to the ground terminal **61**. The pro-

truding portion 311 is band-shaped, and extends on the plate section 31 from one end near the mounting section 33 to the other end near the mating section 32. Preferably, the protruding portion 311 and the mounting section 33 are provided with a gap 312 at the intersection position therebetween. By such an arrangement, the intensity of the plate section 31 may be effectively enhanced. In the present embodiment, the protruding portion 311 is banded, but it will be appreciated that in other embodiments, the protruding portion 311 may also be configured to be a supporting arm formed by bending the plate section 31.

Referring to FIG. 11 together with FIG. 12, the mating section 32 has a mating edge 321 on one side away from the plate section 31. The mating section 32 is provided with an anti-short grounding contact arm 322. One end of the anti-short grounding contact arm 322 is located along the mating edge 321, and the other end is extended along the first direction AA towards the plate section 31. A plurality of the anti-short grounding contact arms 322 are arranged along the second direction BB. A mating depression 323 is formed between the adjacent two anti-short grounding contact arms 322. The first contacting arm 6111 is correspondingly confronting to the anti-short grounding contact arm 322 of the shielding element 30, and the second contacting arm 6112 is resisting against another shielding element 30. The differential signal terminal pair is directly resisting within the mating depression 323. The maximum spacing between a bottom wall of the mating depression 323 and the anti-short grounding contact arm 322 is between 0 and 2.2 mm. Further, the mating section 32 includes a base wall 3201. The anti-short grounding contact arm 322 extends from the base wall 3201 along the third direction CC. The anti-short grounding contact arm 322 connects to the plate section 31 in the first direction AA, and mechanically contacts to the bottom wall of the mating depression 323 in the second direction BB. The maximum spacing between the anti-short grounding contact arm 322 and the base wall 3201 is between 0~1.1 mm. Further, the bottom wall of the mating depression 323 is depressed inwards from the base wall 3201. The maximum spacing between the bottom wall of the mating depression 323 and the base wall 3201 is between 0 to 1.1 mm.

Further, the anti-short grounding contact arm 322 is provided with a first mating tongue 3221 at one end thereof away from the plate section 31. The length of the anti-short grounding contact arm 322 in the first direction AA is between 0.2 to 10 mm, and the length of the first mating tongue 3221 in the first direction AA is between 0 to 6.4 mm.

Further, the bottom wall of the mating depression 323 is provided with a second mating tongue 3231 at one end thereof away from the plate section 31. The length of the second mating tongue 3231 in the first direction AA is between 0 to 6.4 mm. A gap 3232 is defined between the first mating tongue 3221 and the adjacent second mating tongue 3231. While, as can be understood, the gap 3232 may not be formed in other embodiments.

Referring to FIG. 11 and FIG. 12, the bottom wall of the mating depression 323 is also provided with a tuning part 3233. The tuning part 3233 in the preferred embodiment is a tuning hole or a tuning pit. The tuning hole 3233 is a through hole extending through the bottom wall of the mating depression 323. As can be understood, when the tuning part 3233 is configured to be a tuning pit, the tuning pit is a non-through groove. Preferably, the bottom wall of the mating depression 323 has a plurality of the tuning parts 3233. The plurality of tuning parts 3233 may be symmetrically distributed, and may also be radiated distribution.

When the bottom wall of the mating depression 323 is provided with a plurality of tuning parts 3233, the plurality of the tuning parts 3233 may all be tuning holes, or may also all be tuning pits, or may also be part of the tuning holes and part of the tuning pits.

Referring to FIG. 13 and FIG. 14, the back shell or rear stiffener 40 is configured for fixing the plurality of the terminal modules 20 together in a whole. The back shell or the rear stiffener 40 includes a substrate 41, a plurality of insert plates 42 formed by extending outward from one end of the substrate 41 and an extension plate 43 formed by extending outward from the other end of the substrate 41. The insert plates 42 are inserted into the corresponding retaining recesses 752 to fix the terminal modules 20 into a whole. The retaining recess 752 is provided with a first limiting structure 7522. The insert plate 42 is provided with a second limiting structure 421 engaging with the first limit structure 7522. The terminal module 20 and the back shell 40 are secured together by the engagement between the first limit structure 7522 and the second limit structure 421. In the present embodiment, the first limit structure 7522 is formed as a protrusion, and the second limit structure 421 is defined as a groove which is in conjunction with the limit protrusion 7522. Preferably, the limit protrusion 7522 is provided with a first lead surface 7523. The insert plate 42 has a second lead surface 422 formed at one end thereof away from the substrate 41. The first lead surface 7523 is mated with the second lead surface 422 to make the limit protrusion 7522 smoothly inserted into the limit groove 421.

Further, the extension plate 43 is further provided with a secondary slot 431. The insulating body 70 is further provided with a secondary board 702 for mating with the secondary slot 431. The secondary insert board 702 is inserted into the secondary slot 431 so that the back shell 40, the terminal modules 20 can be fixed together. Preferably, the secondary insert board 702 is provided with a bump (not shown). The bump is mated to the secondary slot 431 by interference.

Turn back to FIG. 2, the insulating base 50 is plate-shaped, for matching with and securing the terminal module 20 and the shielding element 30 together as a whole. The insulating base 50 is provided with a plurality of holes for the first mounting portion 612, the second mounting portion 622 passing therethrough.

Compared with the prior art, when the electrical connector 100 of the present invention engages with the complementary connector, a grounding path is established between the shielding element 30, the grounding terminal 61 and the grounding contact of the complementary connector, which thereby increases the electromagnetic isolation between the differential signal terminal pairs, decreases the insertion loss and reduces crosstalk.

Referring to FIG. 15, the present invention further discloses another embodiment of the terminal assembly 80. The structure of the terminal assembly 80 is substantially the same as the structure of the terminal assembly 60, the difference is that, the grounding terminal 81 of the terminal assembly 80 further comprises a third contact arm 8131 electrically connected to the third grounding element. The third contact arm 8131 is formed on the first connection portion 813 and extends outward in the fourth direction. The third contact arm 8131 is formed by an elastic contact arm, or a rigid contact arm. In this embodiment, the third grounding element is the shielding means located between the adjacent two terminal assemblies 80.

Furthermore, the present invention also discloses a grounding structure, comprising the terminal assembly

60/80, a first grounding element and a second grounding element. The first grounding element and the terminal assembly **60/80** are intervalley arranged along the third direction perpendicular to the first direction and the second direction. The grounding terminal **61/81** is simultaneously electrically connected to the first grounding element and the second grounding element. The first grounding element and the second grounding element are respectively disposed on both sides of the grounding terminal **61/81** along the third direction. In the present embodiment, the first grounding element is a shielding plate and the second grounding element is a grounding terminal of the mated complementary connector.

The present invention also discloses an electrical connector assembly **300** composed by the electrical connector **100** and the mating complementary connector **200** as shown in FIG. 16. It should be noted here that, the electrical connector in the present invention is a high-speed, high-density back-plane connector.

It is to be understood, however, that even though numerous characteristics and advantages of preferred and exemplary embodiments have been set out in the foregoing description, together with details of the structures and functions of the embodiments, the disclosure is illustrative only; and that changes may be made in detail within the principles of present disclosure to the full extent indicated by the broadest general meaning of the terms in which the appended claims are expressed.

What is claimed is:

1. A terminal module for assembly into a high-speed, electrical connector adapted to connecting a complementary connector, said high-speed electrical connector having a shielding plate stacked assembled with said terminal module, said terminal module comprising:

a terminal assembly comprising a plurality of conductive terminals, said conductive terminals comprising contacting portions, mounting portions and connecting portions interconnecting said contacting portions and mounting portions; and
an insulating body for securing said connecting portions of said conductive terminals, said insulating body defining a plurality of cutouts thereon with said connecting portions partially exposed therein; wherein an exposed surface of said connecting portion is coated with an insulating thin film.

2. The terminal module as claimed in claim 1, wherein said terminal assembly comprises a plurality of grounding terminals, each grounding terminal having a first contacting portion, a first mounting portion and a first connecting portion for interconnecting said first contacting portion and said first mounting portion; wherein said first contacting portion comprises a first contacting arm electrically connecting to said shielding plate of said connector and a second contacting arm electrically connecting to a grounding contact of the complementary connector.

3. The terminal module as claimed in claim 1, wherein said terminal assembly comprises a plurality of terminals forming differential signal pairs, each of said plurality of terminals comprising a second contacting portion, a second mounting portion and a second connecting portion connecting said second contacting portion and said second mounting portion; and wherein said second contacting portion extends from said second connecting portion along a first direction, said insulating body is provided with a first concession slot adjacent to the second contacting portion; and wherein, in the first direction, said first concession slot is directly confronting to said second contacting portion; and wherein

when said terminal module engages with a complementary connector, part of a signal contact of said complementary connector is located in said first concession slot.

4. The terminal module as claimed in claim 2, wherein said first contacting arm extends outwards from said first connecting portion along a first direction, and a slot is defined between said first contacting arm and said first connecting portion; and wherein said second contacting arm is formed by extending along the first direction from a side edge of said slot that adjacent to said first connecting portion.

5. The terminal module as claimed in claim 4, wherein said first contacting arm comprises a contacting finger and a pair of connecting arms that extending from opposite sides of said contacting finger toward said first connecting portion; and wherein said contacting finger, said pair of connecting arms and said first connecting portion together define said slot.

6. The terminal module as claimed in claim 2, wherein a second concession slot is defined on said insulating body adjacent to said first contacting arm; wherein, in said first direction, said second concession slot is confronting to said first contacting arm; and wherein when said terminal module mates with said complementary connector, the grounding contact of said complementary connector is partially housed in said second concession slot.

7. The terminal module as claimed in claim 2, wherein a contacting region between said first contacting arm and said shielding plate of said electrical connector is deemed as a first contacting region, and a contacting region between said second contacting arm and said grounding contact of said complementary connector is deemed as a second contacting region.

8. The terminal module as claimed in claim 7, wherein said first contacting region and said second contacting region are respectively located at opposite sides of said first connecting portion along a thickness direction of said first connecting portion.

9. The terminal module as claimed in claim 2, wherein a third concession slot is defined in said insulating body adjacent to said second contacting arm, and along said first direction, said third concession slot is confronting to said second contacting arm and said second contacting arm is partially accommodated in said third concession slot.

10. The terminal module as claimed in claim 5, wherein said grounding terminal also comprises a third contacting arm electrically connecting with said shielding plate, and said third contacting arm is formed by extending from said first connecting portion and away from said first contacting portion along a top-to-bottom direction.

11. The terminal module as claimed in claim 1, wherein a thickness of said insulating thin film is between 0.01 mm-0.1 mm.

12. A high-speed electrical connector adapted for engaging with a complementary connector, comprising:

a plurality of terminal modules, each terminal module comprises grounding terminals and differential signal pairs embedded within an insulating body, each differential signal pair having contacting portions, mounting portions and connecting portions for connecting said contacting portions with said mounting portions, said insulating body defining a plurality of cutouts thereon with said connecting portions of said differential signal pairs partially exposed therefrom;
a plurality of shielding plates, each shielding plate stacked arranged between every two adjacent terminal modules;

11

a front cover for organizing said plurality of terminal modules, said front cover having a U-shaped cross-section, said grounding terminals and said differential signal pairs partially accommodated within said front cover; and

a rear stiffener for fixing said terminal modules and said shielding plates together from a rear side thereof; wherein an exposed surface of said connecting portion is coated with an insulating thin film.

13. The high-speed electrical connector as claimed in claim 12, wherein said terminal assembly comprises a plurality of grounding terminals, each grounding terminal having a first contacting portion, a first mounting portion and a first connecting portion for interconnecting said first contacting portion and said first mounting portion; wherein said first contacting portion comprises a first contacting arm electrically connecting to said shielding plate of said connector and a second contacting arm electrically connecting to a grounding contact of the complementary connector.

14. The high-speed electrical connector as claimed in claim 13, wherein said terminal assembly comprises a plurality of terminals forming differential signal pairs, each of said plurality of terminals comprising a second contacting portion, a second mounting portion and a second connecting portion connecting said second contacting portion and said second mounting portion; and wherein said second contacting portion extends from said second connecting portion along a first direction, said insulating body is provided with a first concession slot adjacent to the second contacting portion; and wherein, in the first direction, said first concession slot is directly confronting to said second contacting portion; and wherein when said terminal module engages with a complementary connector, part of a signal contact of said complementary connector is located in said first concession slot.

15. The high-speed electrical connector as claimed in claim 14, wherein said first contacting arm extends outwards from said first connecting portion along a first direction, and a slot is defined between said first contacting arm and said first connecting portion; and wherein said second contacting arm is formed by extending along the first direction from a side edge of said slot that adjacent to said first connecting portion; and wherein said first contacting arm comprises a contacting finger and a pair of connecting arm that extending

12

from opposite sides of said contacting finger toward said first connecting portion; and wherein said contacting finger, said pair of connecting arms and said first connecting portion together define said slot.

16. The high-speed electrical connector as claimed in claim 15, wherein a second concession slot is defined on said insulating body adjacent to said first contacting arm; wherein, in said first direction, said second concession slot is confronting to said first contacting arm; and wherein when said terminal module mates with said complementary connector, the grounding contact of said complementary connector is partially housed in said second concession slot.

17. The high-speed electrical connector as claimed in claim 16, wherein a third concession slot is defined in said insulating body adjacent to said second contacting arm, and along said first direction, said third concession slot is confronting to said second contacting arm and said second contacting arm is partially accommodated in said third concession slot.

18. The high-speed electrical connector as claimed in claim 12, wherein a thickness of said insulating thin film is between 0.01 mm~0.1 mm.

19. The high-speed electrical connector as claimed in claim 12, wherein said front cover comprises a mating wall, a top wall and a bottom wall which together define a containing space for securely receiving terminal modules and shielding plates; and wherein said mating wall, which is configured to cooperate with said complementary connector, is provided with a plurality of mating holes arranged in a matrix.

20. The high-speed electrical connector as claimed in claim 12, wherein said rear stiffener comprises a substrate, a plurality of insert plates formed by extending outward from one end of the substrate and an extension plate formed by extending outward from the other end of the substrate; and wherein the insert plates are inserted into corresponding retaining recesses defined on the insulating body to fix the terminal modules into a whole; and wherein the retaining recess is provided with a first limiting structure and the insert plate is provided with a second limiting structure engaging with the first limit structure to thereby securely connecting the terminal module with the rear stiffener.
